UNITED STATES PATENT OFFICE.

SOREN JENSEN, OF LOS ANGELES, CALIFORNIA.

ADJUSTABLE CAN OPENER AND LIQUID PRESERVER.

Application filed August 31, 1926. Serial No. 132,803.

My invention is an adjustable can opener and liquid preserver to puncture cans containing condensed milk and the like.

An object of my invention is a can opener 5 and also a liquid preserver for use in puncturing cans containing condensed milk or the like, in which the can opener is adjustable to fit cans of different sizes in diameter and the construction being such that a considerable range in size of cans may be accommodated and after the cans are punctured the 10 opener will be held if desired in firm position on a can with the puncturing prongs in the holes punched in the can top.

15 A more specific object of my invention is the formation of a can opener having a handle with a right angular end and having a spring secured thereto. The other end is made with a downward inward incline 20 and has a leaf spring or plate pivotally mounted on the end, held in proper adjusted relation to the bevelled or inclined end by means of a bolt and coiled spring construction. Both of the plates or springs are 25 provided with gripping ribs to engage the upper bead of a can and hold the handle in proper adjustment while the can is being punctured and when the contents of a can are being preserved.

30 My invention will be more readily understood from the following description and drawings, in which—

Figure 1 is a perspective view of my can opener in the relation of being withdrawn 35 from a large diameter can;

Fig. 2 is a section on the line 2—2 of Fig. 1 in the direction of the arrows, showing my opener fitted on the can of larger diameter than the opener device;

40 Fig. 3 is a perspective side elevation showing the opener fitted to a small diameter can;

Fig. 4 is an enlarged end view taken in the direction of the arrow 4, showing the adjustable gripping plate.

45 In the drawings, the handle 1 is provided with a block 2 on one end, this block having a right angular or squared end 3. At the other end, the block 4 extends downwardly from the handle and has an inwardly inclined or bevelled end 5. A pair of prongs 6 are secured in each of the blocks extending downwardly below the lower surface and packing washers 7 are fitted around the prongs on such lower surface.

The gripping plates are constructed substantially as follows:

On the block 3 on the end face 3, a gripping plate 8 is secured by a nail or screw 9 extending through a small aperture or notch 10 in the upper edge and a tensioning screw 11 holds such spring plate closely against the flat side of the block. The end of the plate is provided with an inwardly pressed rib 12 to engage around the bead of a can.

The plate 13 at the other end of the handle fitted against the bevelled or inclined face 5 is provided with a notch 14 at its upper edge through which extends a nail or screw 15. An adjustable limit motion screw 16 extends through the upper end of a slot 17 in the plate and the bolt 18 having a head 19 with a kerf extends through the lower part of this slot. The block 4 is provided with a hole 20 extending therethrough parallel to the handle, the bolt 18 extending 70 through such hole and having a nut 21 threaded on the outer end. A compression spring 22 bears against the nut and the inner surface 23 of the block. It will be noted that the nut is preferably square and 75 that one side fits against the lower surface 24 of the handle 1. This plate is provided with a rib similar to the rib 12.

The manner of use and functioning of my can opener is substantially as follows:

80 The opener when in its normal position has both the plates pressed tightly against the end surfaces 3 and 5 as shown in Figs. 1 and 3. The screw 11 holds the plate 5 closely against the end of the block 2 and the spring 22 acting through the bolt 18 holds the plate 13 tightly against the end 5 of the block 4. Thus for a small can in which the diameter of the can is substantially the same as that between the outer 85 lower corners of the blocks 2 and 4, the plates 8 and 13 fit over the bead of the can without being deflected or moved outwardly to any material extent. Thereby the prongs are brought into contact with the top of the 90 can adjacent the outer edge and may be forced through the can by bearing down on the handle or by striking same with a suitable implement.

If the can is of much larger diameter, 105 the rib of the plate 13 is gripped over the bead of the can on one side and the plate moved or pivoted into the position shown

in Fig. 2 against the tension of the spring 22 acting on the bolt 18, the other plate 8 being slipped over the diametrically opposite side of the can. The prongs are then 5 forced through the can.

With this arrangement it will be noted that the prong in the block 2 punctures the can close to the rim or the cylindrical wall of same, whereas the other prong makes a 10 puncturing hole a considerable distance in from the rim or wall.

In using the cans to pour liquid out of same, the liquid would naturally be poured 15 out of the hole or aperture closest to the outside wall, the other aperture or hole being the air vent. In this manner substantially all the contents of the can may be readily poured out. When it is desired to preserve the contents of the can, the can opener is 20 again fitted to the can top, the prongs being inserted through the hole and jammed down in place, the gaskets 7 forming a substantially air-tight seal especially if a small amount of the contents of the can has been 25 allowed to pour through the openings on to the upper surface of the can.

My invention may be considered as an improvement over that set forth in my application Serial No. 79,390 for can opener 30 and liquid preserver, filed January 5, 1926.

I have illustrated my can opener in a simple form, but it will be nevertheless apparent that it can be changed in general construction or specific details to modify the 35 various features. Such changes would be within the spirit of my invention as set forth in the description, drawings and claims.

Having described my invention, what I 40 claim is:

1. A can opener comprising in combination a handle, a pair of prongs extending 45 downwardly therefrom, a pair of side plates outside the prongs, one of said plates having a pivotal connection to the handle and resilient means to allow said plate to pivot outwardly from the handle.

2. A can opener comprising in combination a handle having a pair of prongs, side 50 plates on the opposite ends of the handle, one of said plates being mounted to have a

movement away from the end of the handle, a spring, and means cooperative between the spring and the plate to maintain the said plate against the end of the handle or allow 55 same to move outwardly therefrom.

3. A can opener comprising in combination a handle, a pair of prongs connected thereto, one of the ends of the handle being substantially parallel to an adjacent prong, 60 the other end of the handle being inclined downwardly and inwardly in relation to an adjacent prong, plates secured to the ends of the handle, one of said plates having substantially a pivoted connection, there being 65 an opening in the handle with a bolt extending therethrough, said bolt engaging the plate and a spring normally retracting the bolt and plate against the end of the handle.

4. A can opener comprising a handle 70 structure having a pair of blocks at each end, prongs extending downwardly from said blocks, one of said blocks having an outer face parallel to the prong secured therein, the other block having an inclined 75 face relative to the prong secured therein, a plate secured to the block having the parallel face, a plate substantially pivotally connected to the inclined face of the other block, said block having a hole therethrough, a bolt extending through the said hole and loosely connected to the plate, and a spring tensioned between the bolt and the block.

5. A can opener as claimed in claim 4, 80 having in addition an adjustable limit motion, means secured to the block and restricting the outward movement of the movable plate.

6. A can opener comprising in combination a handle, a pair of prongs extending 85 downwardly therefrom, washers secured to said prongs, gripping plates secured to the ends of the handle, one of the said gripping plates being inclined downwardly and inwardly and having a substantially pivotal 90 connection to the end of the handle, and a resilient device normally restraining said plate from outward movement from the end of the handle.

In testimony whereof I have signed my 100 name to this specification.

SOREN JENSEN.
